UNITED STATES PATENT OFFICE.

CLARENCE T. OLSON, OF CHICAGO, ILLINOIS, ASSIGNOR, BY MESNE ASSIGNMENTS, TO MARLIN-ROCKWELL CORPORATION, OF JAMESTOWN, NEW YORK, A CORPORATION OF NEW YORK.

BALL RETAINER.

Application filed May 2, 1925. Serial No. 27,495.

This invention relates to ball retainers and is particularly applicable to radial bearings. The invention is fully described in the following specification and shown in the accompanying drawings, in which—

Figure 1 is a front elevation of a ball retainer applied to a set of balls.

Fig. 2 is a reduced front elevation of a blank from which the ball retainer is formed, 10 and

Fig. 3 is a section on the line 3—3, of Fig. 1.

The embodiment illustrated comprises a ball retainer formed from a sheet metal blank, as shown in Figure 2, which has an annular ring 10, having inwardly and outwardly extending fingers 11 and 12. This ring is first dished throughout its length as shown in 10^a in Fig. 3 to a radius substantially equal to the radius of the ball which is indented to fit therein and the fingers 11 and 12 are bent upwardly as shown in dotted line at 11^a and 12^a.

The balls 13 are then placed in the retainer 25 and the fingers 11^a and 12^a bend down over the balls as shown at 11^b and 12^b in Fig. 1. The balls are thus held within the retainer but are permitted to turn in the sockets thus formed.

While I have shown and described but a single embodiment of the invention, it is to be understood that it is capable of many modifications. Changes, therefore, in the construction and arrangement may be made 35 which do not depart from the spirit and scope of the invention as disclosed in the appended claims.

I claim:

1. A ball retainer formed from a sheet of metal comprising an annular ring lying at 40 one side of the path of said balls, fingers extending from the inner and outer edges of said ring around opposite sides of said balls to retain them therein, each finger lying substantially half way round one of said balls. 45

2. A ball retainer formed from a sheet of metal comprising an annular ring lying at one side of the path of said balls, fingers extending from the inner and outer edges of said ring around opposite sides of said balls 50 to retain them therein, each finger lying substantially half way round one of said balls, said fingers being twisted so as to conform to the curvature of the ball and to lie flat thereon. 55

3. A ball retainer formed from a sheet of metal comprising an annular ring lying at one side of the path of said balls, fingers extending from the inner and outer edges of said ring around opposite sides of said balls 60 to retain them therein, each finger lying substantially half way round one of said balls, the inner edges of said fingers lying next to the balls and on substantially a great circle of the ball, the fingers lying on opposite sides 65 of said great circle.

4. A ball retainer formed from a sheet of metal comprising an annular ring, one finger for each ball extending from the inner edge 70 of the ring and one from the outer edge, said fingers extending around said ball and nearly meeting on the opposite side.

CLARENCE T. OLSON.
